UNITED STATES PATENT OFFICE

DAVID H. METCALF, OF BATTLE CREEK, MICHIGAN.

IMPROVEMENT IN TINNERS' SQUARES.

Specification forming part of Letters Patent No. 172,821, dated February 1, 1876; application filed October 2, 1875.

To all whom it may concern:

Be it known that I, DAVID H. METCALF, of the city of Battle Creek, in the county of Calhoun and State of Michigan, have invented certain new and useful Improvements in Tinmen's Squares or Rules; and do hereby declare that the following is a full, clear, and exact description thereof, reference being had to the drawings, and the letters marked thereon, making a part of this specification:

The nature of this invention consists, first, in making one side of a square or rule in such a manner that it will contain the outlines of a set of tinmen's patterns; second, in making the other side of said square or rule with diameters, circumferences, and contents, as will be hereafter described.

In order to enable others skilled in the art to make and use my invention, I will now proceed to describe its construction and use.

Figure 1 is the pattern side of the square or rule. The line through the angle of the square is one side of all of the patterns, the other diagonal lines are the other sides, and each line represents a pattern. The lines are numbered 1 2 3, &c. No. 1 is a large wash-basin. No. 2 is a small water-ladle, and so on until we have a full set of tinmen's patterns.

The measure-patterns marked hereon are the United States standard. The square also contains a complete set of metric-measure patterns.

To illustrate its use: Extend the line through the angle of the square indefinitely, as *a b*; then extend the line No. 38, *c d*, until it crosses *a b* at *e*. Take a pair of dividers, open them upon the square nine and three-eighths inches; then place one point of the dividers upon the point *e* where the lines *a b* and *c d* cross, and draw the curved line *f g*. Set the dividers again thirteen and five-eighths inches, and draw the curved line *h o*; add the locks, represented

by dotted lines, and the pattern will be complete.

This pattern is for a six-quart pan. It takes four pieces for a pan. All of the other lines are for patterns, and are worked in the same manner.

The pattern marked Fig. 3 is about one-sixth its size.

Fig. 2 is the other side of the square or rule, and is for cylindrical work to show its utility. Take eight and a half inches for a diameter; look on the square opposite $8\frac{1}{2}$ inches, and you will find $26\frac{5}{8}$ inches; the circumference, or the size, to make your material for a cylinder eight and a half inches in diameter; opposite $26\frac{5}{8}$ you will find the decimal .246. This is the decimal part of a gallon, and is understood to mean that a can or vessel eight and a half inches in diameter, and one inch in depth, will hold the .246 part of a gallon, or about one quart; therefore, should you desire to make a can to hold one gallon eight and a half inches in diameter, it must be four inches in depth.

I am aware that squares or rules have been made marked with diameters and circumferences; consequently I do not make claim to any part of this combination as my invention; but

What I do claim is—

A square, having in addition to the usual graduations a series of graduations forming the outlines of a set of tinners' patterns, and a series showing the diameters, circumferences, and contents of the vessels, substantially as shown and described.

In testimony that I claim the foregoing I have hereunto set my hand this 28th day of September, 1875.

DAVID H. METCALF.
